United States Patent Office

Des. 233,333
Patented Oct. 22, 1974

233,333

FOOD SERVICE BUILDING

Samuel M. Mills, Jr., 12810 Cherry Lane,
Chesterland, Ohio 44026

Filed Feb. 2, 1973, Ser. No. 328,959

Term of patent 14 years

Int. Cl. D25—03

U.S. Cl. D13—1 B

FIG. 1

FIG. 2

FIG. 3

FIG. 1 is a front elevation view of the food service building of the present invention;

FIG. 2 is a rear elevation view thereof;

FIG. 3 is a side elevation view thereof, looking from right to left in FIG. 1 (the side elevation view thereof looking from left to right being a mirror image of FIG. 3); and

FIG. 4 is a top plan view thereof.

I claim:

The ornamental design for a food service building, as shown and described.
